KEYBOARD PERFORATOR AND COUNTER

Ross A. Lake, Chicago, Ill., assignor, by mesne assignments, to Teletypesetter Corporation, a corporation of Delaware

Application September 21, 1936, Serial No. 101,749

40 Claims. (Cl. 164—112)

This invention relates to composing systems and apparatus, and particularly to apparatus for preparing a control strip for the automatic control of composing machines.

5 Composing machines of the linecasting type are provided with matrices consisting of small brass units carrying indented characters in their edges, which are of different thicknesses, due to the fact that the characters vary in width. To produce lines of type, the matrices are assembled into a line of predetermined definite length before the casting operation is performed, the number of matrices necessary to complete a line varying with the particular matrices already assembled. The length of the line, therefore, is dependent upon the thickness of the several characters or matrices comprising the line.

10 It is necessary, during the preparation of a control strip representing lines of composed matter for the production of the slugs or lines of type, to totalize the various thicknesses of matrices so that the operator will be apprised of the length of line remaining available as each key is operated, and can thus judge the justifiability of the line.

15 The principal object of the present invention is to provide a counting device which is capable of positive, efficient, and rapid operation.

20 To achieve the above and other objects of the invention, the keyboard perforator and counter, according to Patent No. 2,059,250 issued to H. L. Krum is modified to embody the features of the present invention. In addition to the Krum patent, reference should also be had to Patent No. 2,080,424 granted May 18, 1937 and Patent No. 2,083,570 granted June 15, 1937 to E. S. Larson et al., and E. S. Larson, respectively, for a full and comprehensive disclosure of a keyboard perforator and counter in which the features may be embodied.

25 In accordance with the present embodiment of the invention, the keyboard includes key levers, arranged in a manner characteristic of typewriters, which operate through a permutation selector mechanism contained in the housing of the perforator and counter apparatus, to position permutably a series of code discs of a selector to select one of a circumferentially arranged series of rods. A counting barrel or rotor, to which a continuous torque is imparted, is provided with 30 a circumferentially arranged series of slides, an operated one of which cooperates with the selected rods to determine the degree of rotation of the counting barrel. Thus, as the counting barrel is rotated through variable angles ac-

cording to the rod selected, like rotation is imparted to a spiral gear operatively associated with the counting barrel. Through a suitable gear train, variable motion is imparted to a matrix pointer associated with an indicator dial. 5

As the keys are depressed, the matrix pointer will be moved through various cumulative distances corresponding to the widths or thicknesses of the matrices represented by the keys. The variable motion imparted to the matrix pointer may be adjusted for different fonts of type by interposing between the key levers and the selector mechanism for the counting device an interchangeable code bar unit comprising a plurality of pairs of elements, one pair allotted to each key lever and operable thereby. Means is provided for shifting the counting code bar unit from its lower case to upper case positions and vice versa by the shift and unshift key levers respectively, and also to provide means for insuring the prompt return of the matrix pointer to its beginning-of-line position during a single revolution of the release operating clutch mechanism.

20 A more comprehensive understanding of the present invention may be had from the following description, taken in conjunction with the accompanying drawings, wherein like reference characters represent similar parts throughout the several views.

25 In the drawings,

Fig. 1 is a perspective view of a perforator and counter with parts broken away showing the apparatus necessary for a clear understanding of the present invention;

Fig. 2 is a rear perspective view of a portion of the keyboard perforator and counter showing the indicating mechanism;

Fig. 3 is a fragmentary plan view of a modified form of shift mechanism;

Fig. 4 is a cross-sectional view taken on line 40 4—4 of Fig. 3;

Fig. 5 is a sectional view taken on line 5—5 of Fig. 3;

Figs. 6 and 7 are fragmentary sectional views of the adjustable back stop according to the 45 present invention, and

Fig. 8 is a cross-sectional view of the operating shaft taken near the single revolution clutch employed for controlling the return of the index pointer to normal position.

50 Having reference to Fig. 1, it is noted that most of the parts shown have their counterpart in the structure illustrated in Patent No. 2,059,250, the entire perforating mechanism not being shown, but which, nevertheless, is operatively a part of 55

the present invention. In Fig. 1 a plurality of key levers 11 are pivoted on a common rod (not shown) and are normally held in a horizontal position by individual springs (not shown). These 5 key levers extend over a number of pairs of selector bars 12 and 13 included in the perforator selector unit indicated generally by the numeral 14, and the pairs of bars 15 and 16 included in the selecting unit of the counting mechanism indicated generally as 17. Each key lever 11 is arranged to depress one of the bars 12-13 or 15-16 of each pair of bars. Through the medium of rocker arms 18, the bar 12 or 13 lifts the other bar of the pair to reciprocate longitudinally 10 bar 19 cooperatively associated with and sub-jacently disposed to each pair of bars 12 and 13 to impart corresponding movement to the associated pivoted member 21. The members 21, as disclosed in said patent, control the operation of 15 punch interference elements 22 in the tape perforating unit 23. Bars 19 are set in characteristic combinations, and for this purpose, bars 12 and 13 are provided with notched upper edges, the bars of each pair being complements; that is, the 20 high portions of one bar are disposed opposite the low portions of the other bar of the same general pair.

Interposed between the series of key levers 11 and the counter selector unit 17 is a removable 30 and interchangeable code bar unit, indicated generally by the numeral 24, which carries therein a plurality of pairs of coded elements 25. In this manner, there is allotted to each of the key levers 11 a pair of coded elements 25 which coact with 35 the pairs of permutation bars 15 and 16 of the counter selecting unit 17.

The removable code bar unit 24 for carrying the pairs of coded elements 25 comprises a channel-shaped member having a webbed portion 26 40 and side walls 27 and 28, which are, in turn, provided with flanges 29 and 31, respectively, (Fig. 4). The web 26 is provided with rectangular apertures 32 (Fig. 3) to guide the vertical projections 33 and 34 of the coded elements 25. The flanges 29 45 and 31 have notches in vertical alignment with the apertures 32 to insure the vertically guided movement of the coded elements 25.

The coded elements 25 are retained in their uppermost positions by individual retention 50 springs 35, each of which, as indicated in Fig. 4, comprises a coil spring having its extremity extended tangentially thereto and oppositely directed therefrom, which, in turn, terminates in laterally disposed portions 36 (Figs. 1 and 4) 55 adapted to coact with the inner surface, respectively of projections 33 and 34 of the coded elements 25. These springs 35 are mounted upon a rod 37 carried in the unit 24. A guide member 38 guides the extremities of the springs 35. With 60 retention springs according to this arrangement, the code elements 25 are readily removable and insertable, and are arranged as a floating construction. To insert a pair of code elements 25, they need only be assembled by means of their 65 dowel pins and slid up into the notches in flanges 29 and 31 and into the corresponding apertures 32 until portions 36 of spring 35 engage the undercut portions of projections 33 and 34, the spring then acting to urge the pair of elements 70 25 upwardly to press the shoulders 39 against the flanges 29 and 31. The pair of elements 25 is readily removable by urging the pair downwardly under slight pressure, thus flexing the tangentially extended portions of the spring 35 75 until the ends 36 thereof slip over the inner apical

portions of projections 33 and 34 of the code elements 25.

A shiftable carrier or cradle, indicated generally by the numeral 41, controls the movement of the removable code bar unit 24 from the shift or front position to the unshift or rear position, and vice versa. Carrier 41 consists of a framework comprising a pair of channelled guides 42 and 43, Fig. 4, suitably spaced apart to provide guideways for the insertion and removal of code bar unit 24. As shown in Fig. 4, the carrier 41 is mounted at its four corners on corner posts 44 which, in turn, are supported upon links 45, pivotally connected to the posts 44 and brackets 46, mounted on base portion 47. The shifting of carrier 41 is accomplished in parallel motion manner by shift mechanism which, according to the present invention, is controlled by the shift key lever 48 and unshift key lever 49, Fig. 1.

In order to associate the proper projections 58 20 on the counting code elements 25 with the proper counting selector bars 15 and 16, it is necessary to shift the position of the code bar unit 24 from right to left, or vice versa, as viewed in Fig. 4, which is from front to rear, or vice versa, of the 25 keyboard apparatus. This movement is accomplished, as previously indicated, by means of the shift and unshift levers 48 or 49, having reference to Fig. 1. Suitably carried in the portion 47 are bell cranks 51 and 52 pivoted at 53 and 30 54, respectively. The horizontal arms of bell cranks 51 and 52 are adapted to coact with shift and unshift key levers 48 and 49, and the depending arms of bell cranks 51 and 52 are pivotally connected to a bar 55 which, in turn, is pivoted 35 at each end to bell crank levers 56, also pivotally carried on portion 47. The other arms of the bell crank levers 56 are pivotally articulated to downwardly projecting studs or pins 57 on the carrier 41. With this arrangement, the shifting 40 of the carrier 41 is accomplished by depressing either the shift key lever 48 or the unshift key lever 49 to rotate their individual bell cranks 51 or 52. Assuming that the unshift key lever 48 is depressed, bell crank 51 will be rotated in a 45 counterclockwise direction to move bar 55 rightwardly, whereupon bell cranks 56, articulated to bar 55, will be rotated counterclockwise. The rotation of bell cranks 56 will, through pins or studs 57, cause the carrier 41 to be shifted rearwardly upon the supporting links 45. Conversely, when the shift key lever 49 is depressed, bell crank 52 will be rotated in a clockwise direction to move the bar 55 leftwardly, whereupon bell cranks 56 55 will be similarly rotated which, through studs 57, will cause the carrier 41 to be shifted frontwardly upon links 45.

When any key lever 11 is depressed, the selector bars 15 and 16 will be moved in accordance with the location of the projections 58 on the code elements 25 to cause the movement of the permutation bars 59 (which are operatively associated with the pairs of selector bars 15 and 16 in a manner similar to the association of bars 19 with selector bars 12 and 13) in various permutations. As indicated in Fig. 4, the code projections 58 on one of the elements 25 are effective in one position, and the projections 58 on the other element 25 of the pair are effective in another position. The carrier 41 is shown in Fig. 4 70 in its right-hand or unshift position, in which position, the projections 58 of the rear element 25 are observed as being in cooperative relation with the selector bars 15 and 16. In the position shown, the projections 58 of the front element 75

25 are observed as being out of cooperative relation with bars 15 and 16. When the carrier 41 is moved to the shift or leftward position, the projections 58 on the front element 25 will be disposed in cooperative relation with the bars 15 and 16, and the projections of the rear element 25 will be out of cooperative relation with bars 15 and 16.

The bars 59, Fig. 4, as fully described in Patent No. 2,059,250, are operatively connected to a corresponding series of Y-shaped members 61, (Fig. 1) which are adapted to be positioned in accordance with the operation of the permutation bars 59 to control the setting of a plurality of notched discs 62, forming part of a code disc selector, indicated generally by the numeral 63. Individual to each of the members 61 and notched code discs 62 is a transfer lever 64, which is pivotally mounted on a rod 65 carried in a bracket (not shown) operated, in a manner described in Patent No. 2,059,250, to reciprocate the transfer levers 64 vertically. Upon reciprocation, the transfer levers 64 will be moved into cooperative relation with the Y-shaped members 61; that is, whether the members 61 are swung to the right or left, as viewed in Fig. 1, the abutments 60 of the transfer levers 64 will engage or be free of one or the other of the abutments 70 on the upper end of Y-shaped members 61 to cause the discs 62 to be rocked in either a clockwise or a counterclockwise direction. With the Y-shaped members 61 operated in varying permutations in accordance with the movement of the permutation bars 59, the discs 62 will likewise be rotated in varying permutations and will, for each permutation, cause an alignment of notches formed in the periphery of the discs.

Cooperating with the notches in the discs 62 are a plurality of rods 66 arranged with anti-friction rollers 67, there being a rod individual to each set of aligned notches. Each of the rods 66 is centripetally biased by an individual spring 68. In this manner, the rods 66 tend to move radially toward a common center into the notches of the discs 62, but inasmuch as the notches are arranged so that for each setting of the discs, only one group of notches will be in transverse alignment, only one of the rods 66 for each selection will move into the notches. Also, the notches in the discs 62 are arranged so that when the discs are moved for a subsequent selection, the previously selected rod 66 will be cammed outwardly against the action of its associated spring 68. Carried on the right-hand end of each of the rods 66 is a stop member 69 (Fig. 1), which slides in slots formed in a circular member 71.

To the right of the code disc selector 63 (as viewed in Fig. 1) is a counting barrel or rotor 72 forming a part of the counting mechanism, which is rotated by power communicated from a continuously rotating motor (not shown), through a friction clutch 73. The counting unit 72 comprises a plurality of circumferentially arranged slides 74, which are longitudinally slidable and adapted to coact with the stop members 69 to determine the degree of rotation of unit 72, and any of the slides 74 which are found in the zero position are operated invariably by a lever (not shown), while a previously operated slide is simultaneously restored to its normal or non-operated position by a collar 75 to accomplish, through the coaction of an operated slide 74 and a selected stop member 69, the incrementally progressive movement of the counting unit 72. The counting unit 72 includes a shaft 76 on which is formed

a worm 77. Attention is directed herein to the structural feature of counting unit 72 in that it is of a very small diameter, thereby permitting a high speed of rotation. By having the parts near the axis of rotation, the centrifugal action is reduced, and the amount of inertia is materially less, which makes possible the rotation of the parts at very high speeds.

As previously mentioned, the slides 74 cooperate with the rods 69 to arrest the rotation of the counting unit 72, which is driven, through friction clutch 73, to cause a corresponding degree of rotation to worm 77. The rotation of the worm 77, which meshes with a gear 78 secured to a shaft 79, causes the corresponding angular rotation of a shaft 81, through gears 82 and 83. A worm 84 is fixed to the other extremity of shaft 81 (Fig. 2) and meshes with a worm wheel 85.

As shown in Fig. 1, the indicator comprises a bracket 87, which carries pivotally thereon, through the instrumentality of member 160, a dial 88, which is provided adjacent to its outer arcuate edge with a scale or series of graduations representing increments of a maximum length of line. The reverted end of a matrix pointer 86 moves along this edge of the dial from left to right, towards zero, in response to the totalization of the matrix thicknesses by the counting mechanism. Thus, the distance from the pointer 86 to zero indicates the amount of space left in the line to be filled with matrices if the line contains no space bands. However, if space bands are inserted in the line, the space remaining to be filled varies with the number of space bands inserted. Consequently, to indicate the justifiability of the composed line, a pair of space band pointers 89 and 91 are provided, the distance between the pointers 89 and 91 indicating the amount of expansibility of the space bands.

In the embodiment shown, the dial 88 is articulated to the minimum space band pointer 91, through a pin 92, and is movable with said pointer. The space left in the line to be filled when space bands are inserted is represented by the distance between the matrix pointer 86 and any point between space band pointers 89 and 91. The manner of effecting the differential or proportional movement of pointers 89 and 91 toward the left (from their zero position) is fully set forth in Patent No. 2,059,250.

As shown in Fig. 2, the matrix pointer 86 is associated with the scale 88, and is separated from the counting clutch to enable the introduction of an adjusting mechanism for varying the movement, or rate of deflection of the matrix pointer 86 with respect to the fixed movement of the counting mechanism 72, to permit direct pica measurement of lines to keybar "ems". The matrix pointer 86 is mounted for rotation on a pivot stud 95 fixed to the bracket 87. Also associated with the matrix pointer 86, to rotate therewith on shaft 95, is a pinion 97.

The counting clutch, as shown in Fig. 5, comprises a shaft 98, which terminates at one end in a flange or disc 99, the other end of which is threaded to receive a nut 101. Shaft 98 is carried in a flanged sleeve member 102, and attached to the flange 105 of member 102 is the worm gear 85. The assembly, comprising shaft 98 and sleeve 102, is mounted in a bearing or bracket 103 carried on the base 104 (Fig. 2). Interposed between the flange 99 and the flange 105 are a pair of friction discs 106 and an intermediately disposed gear 107. Pressure is imparted to the fric-

tion discs 106, to constrain the gear 107 for rotation with worm gear 85, by a compression spring 108, which is compressed between the nut 101 and a nut 109 carried on the sleeve 102. A friction washer 111 is disposed between the nut 109 and the vertical bearing portion of bracket 103. With the arrangement so far disclosed, the rotation of the counting unit 72 is imparted, through gears 73 and 82 on shaft 79 and gear 83 on shaft 81 to worm 84, to rotate worm gear 85, to impart, in turn, rotation to the gear 107. Meshed with gear 97 is a vertically disposed rack member 112, carried in guide brackets 110 and 113 mounted on frame 96, Fig. 2. Carried on rack 112 is a stud 114 which coacts pivotally with one end of a lever 115, adjustably fulcrumed at 116. Fulcrum 116 comprises a block member 117 (Fig. 1) and receives a screw member 118 in such a manner that the block 117 is adapted, when screw 118 is turned by the knurled cap 120, to travel along a diagonal slot 119 (Fig. 2) in bracket 96. Lever 115 is provided with a slot 121 to provide, together with slot 119, a means for adjustably controlling the vertical movement of rack 112. The left end of lever 115 (as viewed in Fig. 2) cooperates with a stud 122, carried on a rack member 123 suitably guided for vertical movement on the bracket 96. Rack 123 meshes with the gear 107 associated with the worm gear 85 (Figs. 2 and 5) in such manner that, when the gear 85 is rotated under the control of the counting mechanism 72, rack 123, through the instrumentality of friction discs 106 and gear 107, is given a downward movement, which movement, through stud 122, is imparted to lever 115, causing it to rotate in a counterclockwise direction about fulcrum 116 to elevate the rack 112, which causes, through gear 97, the matrix pointer 86 to move toward the left (Fig. 2).

40 A lever 125, pivoted at 126 on bracket 96 and actuated by a spring 127, is provided to effect the return of rack 123 to its uppermost vertical position when the clamping effect of flange 99 on gear 107 is relieved.

45 To effect the prompt return of the rack 123, and hence matrix pointer 86, to its beginning-of-line position, the present invention provides a booster or quick return means, comprising a bell crank 128, pivoted on shaft 129 carried in a bracket 96 secured to bracket 103. Bell crank 128 has an arm 131, to the end of which is connected one end of a spring 132, the other end of which is connected to lever 125. The other arm 133 of bell crank 128 cooperates with the depending arm 134 of a bell crank lever 135 pivoted at 130. Lever 135 is normally employed to unclamp the counting clutch, through the medium of its vertical projection 136. The unclamping of the counting clutch is effected through link 137, pivoted at the extremity of the horizontal arm of lever 135, and pivotally articulated to a lever 138, pivoted at 139 to a bracket 141, mounted on base 104 (Fig. 2). As shown in Figs. 1 and 8, the extremity of lever 138, opposite to the link 137, is provided with a follower roller 142, adapted to coact with a cam 143, associated with a clutch 144, carried on the operating shaft 145. Also, associated with clutch 144 is a clutch throw-out lever 146, with which is associated a vertical latch arm 147, which functions to disengage the clutch throw-out lever 146 from stop 180. Latch 147 is carried at the extremity of a lever 148 which, as shown in Figs. 2 and 8, is pivoted on pivot 139. To the extremity of lever 148, opposite to that at 75 which latch 147 is carried, is pivoted a link 149

(Figs. 2 and 8), which provides an interconnection between lever 148 and the key lever 11 (Fig. 8) assigned to the elevator or end-of-line signal.

The cam 143, as shown in Fig. 8, carries a pin 140 aligned in its rotation with an arm 150 complementary to the latch arm 147. The pin 140 is arranged with respect to the clutch throw-out cam surface 100 to operate the member 150 just prior to the completion of the cycle of rotation of the cam 143 and causes the rotation of the latch member 147 and the restoration of the lever 146 to its normal position or in a position to arrest the rotation of the driven portion 154 of clutch 144 and cause it to move axially of the shaft 145 or to the right, as viewed in Fig. 1. The purpose of the pin 140 and the arm 150 is to ensure that the cam 143 will invariably be arrested for each cycle of rotation. In other words, the clutch 144 is referred to as a single revolution clutch in that for each release of the driven portion 154, it makes a single complete revolution before it is disengaged from the driving portion 155 which is fixed to the shaft 145.

Accordingly, upon the depression of the elevator key, downward movement will be imparted to link 149 to cause lever 148 to rotate counterclockwise (as viewed in Fig. 2) to raise lever 147 (Fig. 1) to effect the release of clutch throw-out arm 146, and to permit the engagement of clutch 144 to cause the rotation of cam 143 through a single cycle of rotation. Through cam 143 and follower roller 142 (Fig. 1), clockwise rotation is imparted to lever 138 (as viewed in Fig. 2) to cause, through link 137, the clockwise rotation of bell crank 135, which, through shaft 98 (Fig. 5), causes the counting clutch to become unclamped. Simultaneously with the unclamping function, the depending arm 134 of bell crank 135 acts on arm 133 of lever 128 to cause lever 128 to be rotated counterclockwise, which movement, through arm 131, stretches spring 132, and thus, through spring 132, causes lever 125 to rotate in a clockwise direction. It is understood that the motions just described are sharp and sudden, and hence the momentum imparted to lever 125, through spring 132, is such as to impart a sharp upward movement to rack 123, to effect the return of rack 123 to its normal or beginning-of-line position during the time that gear 107 is unclamped, and before it is again clamped.

The return of matrix pointer 86 is effected by means of a spring 151, through a lever 152, which is provided at its extremity with a gear segment 153, which meshes with a gear 97 associated with matrix pointer 86. Thus, when rack 123 is returned to its vertical stop position, lever 115 is free to be rotated in a clockwise direction by the action of spring 151, which causes lever 152 to rotate in a counterclockwise direction to impart clockwise rotation to matrix pointer 86 and gear 97. The clockwise movement of gear 97 causes rack 112 to move downwardly and, through stud 114, imparts clockwise rotation to lever 115.

Rack 123 cooperates with two vertical stops; namely, a fixed stop 155 and an adjustable stop 156 (Fig. 2). The fixed stop 155 comprises, in the present embodiment, a set screw mounted in lug 158 on bracket 96, and is set so that when rack 123 abuts against stop 155, the slots 119 and 121 are parallel and coincident. The adjustable stop 156 is adapted to mesh with an adjusting screw 159, supported vertically in brackets 164 and 165, and provided with a cap portion 166. As indicated in Figs. 6 and 7, adjustable stop 156 comprises a block provided with a

threaded groove on its edge to correspond to the screw 159 so that block 156 can be drawn, at will, out of engagement with screw 159. To enable the block 156 to be readily and easily withdrawn from the screw 159, a pair of cam levers 167 are provided which are pivoted to stem 168 integral with block 156. Levers 167 are normally held in the position shown in Fig. 6 by means of a coiled spring 169. When the levers 167 are pinched or drawn together to the position shown in Fig. 7, the block 156 is withdrawn from engagement with screw 159 and in this manner block 159 may be shifted vertically to achieve a quick adjustment of the adjustable back stop. After the desired stop position is approximated, the cap 166 (Fig. 2) is turned to effect, through screw 159, a micrometer or fine adjustment of block 156. As noted in Fig. 2, rack 123 is provided with a lateral portion 171 which abuts the 20 adjustable stop 156.

Modification

In Figs. 3 and 4 is shown a modified form of the shift mechanism for shifting the counting code 25 bar unit, under the control of an additional pair of selector bars 12 and 13 in the perforator selector unit 14. As indicated in Fig. 3, a bar 19 is provided with angular members 161, which are pivotally articulated to a pair of bell cranks 30 162, pivotally carried on base 47, the other arm of the bell crank being pivotally articulated to studs 163 (comparable to studs 57 in Fig. 1).

Thus, upon the depression of the shift or unshift key levers, the pair of bars 12 and 13, associated with the shift mechanism, is operated to cause, through rocker members 18, the longitudinal shifting of bar 19 individual thereto. Thus, the depression of the shift key lever will cause bar 19 to be shifted rightwardly, as viewed in Fig. 3, to impart counterclockwise rotation to bell crank 162, thus causing, through studs 163, the carrier 41 to be moved rearwardly. Then, when it is desired to shift the carrier 41 to its other shift position, the opposite shift key will be operated, which will cause, through rocker arms 18, the bar 19 to be shifted leftwardly (Fig. 2) to cause bell cranks 162 to be rotated clockwise, thus causing the carrier 41 to be moved forward.

50 Although the present invention has been disclosed in connection with the perforator and counter, it is, of course, understood that the invention is capable of embodiment in many and varied applications other than that specifically disclosed without departure from the spirit and scope of the invention as defined in the appended claims.

What is claimed is:

1. In an apparatus for preparing control strips for linecasting machines, an indicating device including a scale, an index pointer, a counting device, means to control the operation of said counting device incrementally, means controlled by said counting device to control the actuation of said index pointer with respect to said scale, motive means including a single revolution clutch, means associated with said motive means to render said counting device ineffective to actuate said second recited means, and means to insure the return of said second recited means to its normal position during a single revolution of said clutch.

2. In a keyboard apparatus, a series of keys, a mechanism comprising means to totalize various additive amounts and to indicate continuously

such totalizations, a unit carrying a plurality of coded elements, pivoted carrier means for receiving and supporting said unit, said unit being interchangeableably insertable in said carrier means in operative relation to said keys for interchange according to the font of type to be used, and means controlled by certain of said keys to pivot said carrier means to determine the shift or unshift position of said unit. 5

3. In a keyboard apparatus, a series of keys, a 10 counting mechanism comprising means to totalize various additive amounts and to indicate continuously such totalizations, a unit carrying a plurality of coded elements, pivoted carrier means for supporting said unit, said unit being 15 interchangeableably insertable in said carrier means in operative relation to said keys for interchange according to the font of type to be used, a pair of studs mounted on said carrier means, means comprising a pair of bell crank levers having a 20 common link therebetween associated with said studs, and means articulated to said common link individual to certain of said keys and controlled thereby to pivot said carrier means to determine 25 the shift or unshift position of said unit.

4. In a keyboard device, a counting device, a scale, indicating means movable with respect to said scale in accordance with the key operated, an element associated with said counting device, another element associated with said indicating 30 means, a proportionally adjustable instrumentality interconnecting said elements to vary the operative relationship between said counting device and said indicating means, and means effective under certain operating conditions to actuate said 35 first recited element positively and independently of said operative relationship.

5. In combination, a counting device, a scale, indicating means movable with respect to said scale, an element associated with said counting 40 device, another element associated with said indicating means, means cooperatively related to said elements to vary the operative relationship between said counting device and said indicating means, and means effective under certain 45 operating conditions to actuate said first recited element positively and independently of said operative relationship.

6. In an apparatus for preparing control strips for typographical machines, a counting device, 50 an indicating means, an element associated with said counting device, another element associated with said indicating means, means cooperatively related to said elements to vary the operative relationship between said counting device and 55 said indicating means, and means effective under certain operating conditions to actuate said first recited element positively and independently of said operative relationship.

7. In an apparatus for preparing control strips for typographical machines, a counting device, an indicating means, a rack member associated with said counting device, a rack member associated with said indicating means, an element cooperably interposed between said rack members, means associated with said element to vary the effectiveness of said counting device upon 65 said indicating means, and means effective under certain operating conditions to actuate said first recited rack member positively and independently 70 of said operative relationship.

8. In an apparatus for preparing control strips for linecasting machines, an indicating device including a scale, an index hand, a counting device, means to control the operation of said 75

- counting device incrementally, means controlled by said counting device to control the actuation of said index hand with respect to said scale, motive means including a single revolution clutch, clamping means to effectuate the movement of said index hand, means associated with said motive means to render said clamping means ineffective, and means associated with said last mentioned means to insure the return of said 5 second recited means to its normal starting position during a single revolution of said clutch.
9. In a keyboard apparatus, a series of keys, an indicating device including a scale, an index hand, a counting device, means responsive to the actuation of certain of said keys to control the operation of said counting device incrementally to actuate correspondingly said index hand with respect to said scale, clamping means to effectuate the movement of said index hand, 10 motive means including a single revolution clutch, means associated with said motive means and responsive to the actuation of another of said keys to render said clamping means ineffective, and means associated with said last mentioned 15 means to insure the return of said index hand to its normal position during a single revolution of said clutch.
10. In a keyboard apparatus, a series of keys, a counting mechanism comprising means to 20 totalize various additive amounts and to indicate continuously such totalizations, a unit carrying a plurality of coded elements, pivoted means for supporting said unit provided with a pair of studs, means comprising a pair of bell 25 crank levers having a common link therebetween associated with said studs, and means articulated to said common link and controlled by certain of said keys to shift said pivoted means to determine the position of said unit.
11. In a keyboard apparatus, a series of keys, a counting mechanism comprising means to 30 totalize various additive amounts and to indicate continuously such totalizations, a unit carrying a plurality of coded elements, pivoted means for supporting said unit provided with a pair of studs, means comprising a pair of bell 35 crank levers having a common link therebetween associated with said studs, and means comprising a pair of parallel code bars responsive selectively to certain of said keys to shift, through 40 said link, said pivoted means to determine the position of said unit.
12. In apparatus for preparing control strips for typographical machines, a scale, an indicating means, a counting device for moving said means with respect to said scale various incremental amounts representative of matrix widths, a ratio mechanism comprising a proportionally 45 adjustable instrumentality interposed between and operably related to said device and said means to vary the operative relationship between 50 said device and said means, motive means including a single revolution clutch, means associated with said motive means to render said counting device ineffective to move said indicating means, and means associated with said last mentioned means to insure the return of said indicating means to its normal position during 55 a single revolution of said clutch.
13. In an apparatus for preparing control strips for typographical machines, a counting device, an indicating means, an element associated with said counting device, another element associated with said indicating means, means cooperatively 60 related to said elements to vary the operative 65

relationship between said counting device and said indicating means, an adjusting screw, and means for limiting the normal return movement of said first recited element, said last recited means being movable integrally within a wide range and including a portion meshable with said screw to provide adjustability within a narrow range. 5

14. In an apparatus for preparing control strips for typographical machines, a counting device, an indicating means, an element associated with said counting device, another element associated with said indicating means, means cooperatively related to said elements to vary the operative relationship between said counting device and said indicating means, an adjusting screw, and cam release means for limiting the normal return movement of said first recited element, said last recited means being movable integrally within a wide range and including a portion meshable, under the control of cam levers, to provide adjustability within a narrow range. 10

15. In combination, in an apparatus for preparing control strips for typographical machines, a counting organ, means for effecting fixed actuations of said counting organ for each operation thereof, indicating means controlled by said counting organ, a ratio mechanism for varying the effect imparted by the fixed actuations of said counting organ upon said indicating means, an adjusting screw, and cam controlled limiting means for said ratio mechanism, movable integrally within a wide range and including a portion meshable with said screw to provide adjustability within a narrow range. 15

16. In a keyboard perforator and counter, a perforating device, a counting device, selector mechanisms for said devices, a unit carrying a plurality of coded elements, pivoted means for supporting said unit provided with a pair of studs, means comprising a pair of bell crank levers having a common link therebetween, and means articulated to said common link and controlled selectively through one of said selector mechanisms to shift said pivoted means to change the position of said unit with respect to the other of said selector mechanisms. 20

17. In an apparatus for preparing control strips for linecasting machines, a scale, an index pointer, spring return means therefor, a counting device, means to control the operation of said counting device incrementally, frictionally driven means controlled by said counting device to control the actuation of said index pointer with respect to said scale, motive means including a single revolution clutch, disabling means associated with said motive means to render said counting device ineffective to actuate said frictionally driven means, and means associated with said disabling means to insure the return of said frictionally driven means to its normal position during a single revolution of said clutch independently of the action of said spring return means. 25

18. In a keyboard device, a scale, indicating means movable with respect to said scale, a counting device, means to control the operation of said counting device, an element actuated by said counting device, a member associated with said indicating means and controlled through the instrumentality of said element, spring return means for said member, means for disabling said counting device, and means effective in response to said disabling means to actuate said 30 35 40 45 50 55 60 65 70 75

element positively and independently of the action of said spring return means upon said member.

19. In a keyboard apparatus, a series of keys, 5 an indicating device including a scale, an index hand, spring return means therefor, a counting device, means responsive to the actuation of certain of said keys to control the operation of said counting device incrementally, rack and gear means associated with said counting device, clamping means to effectuate through said rack and gear means the movement of said index hand, motive means including a single revolution clutch, disabling means associated with said 10 motive means and responsive to the actuation of another of said keys to render said clamping means ineffective, and means associated with said disabling means to insure the return of said rack and gear means to its normal position during a 15 single revolution of said clutch independently of the action of said spring return means.

20. In a keyboard device for preparing control strips for linecasting machines, a counting mechanism operated in incremental amounts 25 representative of matrix widths, a plurality of elements, means operated permutably for invariably selecting one of said elements, a counting organ controlled through said means and coacting with the selected element for determining 30 the extent of operation of said counting mechanism, an indicating means responsive to the action of said counting organ, a slidable element associated with said counting mechanism, a slidable member associated with said indicating means, a proportionally adjustable instrumentation interconnecting said slidable element and slidable member to vary the operative relationship between said counting mechanism and said indicating means, and means independent of said instrumentation operable under certain operating conditions to actuate said 35 slidable element positively and independently of said slidable member.

21. In an apparatus, a plurality of elements, 45 means to enable the actuation of said elements, a counting device comprising a plurality of circumferentially arranged slidable members, cam controlled means to control the operation of said device incrementally through the cooperation 50 of said members and said elements, indicating means responsive to the action of said cam controlled means, a slidable element associated with said counting device, a member associated with said indicating means, a proportionally adjustable instrumentation 55 cooperatively related to said slidable element and said slidable member to vary the operative relationship between said counting device and said indicating means, and means independent of said instrumentation operable under certain operating conditions to actuate said slidable element positively 60 and independently of said slidable member.

22. In an apparatus, a counting device, means for actuating said device including a series of 65 operable elements, a plurality of stop members, means for operating an element invariably at a fixed point representative of the zero position, cam controlled means for operating the elements to cause their cooperation with said members 70 to effect the corresponding operation of the counting device, a registering means responsive to the action of said cam controlled means, a gear operated element associated with said counting device, a member associated with said 75 registering means, adjustable means cooperative-

ly related to said gear operated element and said member to vary the operative relationship between said counting device and said registering means, and means independent of said adjustable means operable under certain operating conditions to actuate said gear operated element positively and independently of said member. 5

23. In an apparatus, a plurality of elements, means to enable the actuation of said elements, a uni-directional counting organ comprising a 10 plurality of circumferentially arranged slidable members, means effective through the cooperation of said members and said elements to control the incremental progressive movement of said counting organ, indicating means responsive 15 to the actuation of said organ, a gear operated element associated with said counting organ, an instrumentality associated with said indicating means, adjustable means cooperatively related to said element and said instrumentality to vary the 20 operative relationship between said counting organ and said indicating means, and means independent of said adjustable means operable under certain operating conditions to actuate said gear operated element positively and independently of said instrumentality. 25

24. In combination with a keyboard perforator suitable for the production of perforated tape representing lines of composition, a counting mechanism operated in incremental amounts 30 representative of matrix widths, a plurality of elements, means operated permutably for invariably selecting one of said elements, cam operated means controlled through said means and coacting with the selected element for determining 35 the extent of operation of said counting mechanism, an indicating means responsive to the action of said cam operated means, a rack element associated with said counting mechanism, a rack member associated with said indicating means, adjustable means associated with said rack element and said rack member to vary the effectiveness of said counting mechanism upon said indicating means, and means independent of said adjustable means operable under 40 certain operating conditions to actuate said rack element positively and independently of said rack member. 45

25. In a keyboard device, a plurality of keys, a shaft, an indicator, motive means constantly 50 tending to govern the incrementally progressive movement of said shaft, means invariably controlled by said keys to release said shaft for rotation, gear and rack means to transfer the movement of said shaft to said indicator, a 55 special key, disabling means controlled by said special key to render said gear and rack means ineffective to move said means, and means controlled by said disabling means to operate said gear and rack means reversely independently of 60 said indicator. 65

26. In combination in an apparatus for preparing control strips for typographical machines, a signal determining means operable variably to 65 impress signals on said control strip, a counting organ, means for effecting fixed actuations of said counting organ for each operation thereof corresponding to the variable operation of said signal determining means, indicating means controlled by said counting organ, a divisible ratio 70 mechanism for varying the effect imparted by the fixed actuations of said counting organ upon said indicating means, means having a definite period of operation for rendering the actuations of said counting organ ineffective during said 75

period, and booster means controlled by said last recited means to impart reverse action to one divisible portion of said ratio mechanism to insure its complete restoration during said period of operation.

5. 27. In a keyboard device, a counting device, a scale, an index hand and spring return means therefor, mechanism nonconcentric with said index hand and including friction means to move 10 said index hand with respect to said scale in accordance with the operation of said counting device as determined by the key operated, means invariably controlled by one of said keys to render said friction means ineffective to move said index hand, and means controlled by said last recited means to insure the restoration of said friction means to its initial position independently of the restoration action of said spring return means.

28. In a keyboard device, a counting device, a scale, an index mechanism and spring return 20 means therefor, mechanism non-concentric with said index mechanism and including gear and rack means to move said index mechanism with respect to said scale in accordance with the operation of said counting device as determined by the key operated, means invariably controlled by one of said keys to render said gear and rack means ineffective to move said index mechanism, and means controlled by said last recited means 30 to insure the restoration of said gear and rack means to its initial position independently of the restoration action of said spring return means.

29. In combination in a machine for preparing control strips for typographical machines, a 35 counting organ, clutch means comprising a rack member responsive to fixed actuations of said counting organ, indicating means comprising a rack member controlled by said clutch means, means comprising a proportionally adjustable 40 instrumentality for varying the effect of the fixed actuations of said counting organ upon said indicating means, said instrumentality constrained to move invariably with one only of said rack members, disabling means to render said clutch 45 means ineffective to control said indicating means, and means controlled by said disabling means to insure the restoration of said first recited rack member to its initial position independently of the like restoration of said second 50 recited rack member.

30. In an apparatus for preparing control strips for linecasting machines, a scale, an index pointer, spring return means therefor, a counting device, means to control the operation of said counting device incrementally, control means 55 controlled by said counting device to control the actuation of said index pointer with respect to said scale, motive means including a single revolution clutch, disabling means associated with 60 said motive means to render said counting device ineffective to actuate said control means, and yieldable means associated with said disabling means to insure the restoration of said control means to its normal position during a single revolution of said clutch independently of the action of said spring return means.

31. In an apparatus for preparing control 70 strips for linecasting machines, a scale, an index pointer, spring return means therefor, a counting device, means to control the operation of said counting device incrementally, control means controlled by said counting device to control the 75 actuation of said index pointer with respect to said scale, motive means including a single revolution clutch, disabling means associated with

said motive means to render said counting device ineffective to actuate said control means, and anti-shock means associated with said disabling means to insure the restoration of said control means to its normal position during a single revolution of said clutch independently of the action of said spring return means.

32. In a keyboard device, a scale, indicating means movable with respect to said scale, a counting device, means to control the operation 10 of said counting device, an element actuated by said counting device, a member associated with said indicating means and controlled through the instrumentality of said element, spring return means for said member, means for disabling 15 said counting device, and a booster means effective in response to said disabling means to actuate said element positively and independently of the action of said spring return means upon said member.

33. In an apparatus for preparing control strips for linecasting machines, indicating means, spring return means therefor, a counting clutch, an element operated by said clutch for controlling 20 said indicating means, disabling means for 25 imparting to said clutch a definite period of ineffectiveness, and means controlled by said disabling means to effect during said period the restoration of said element to its initial position independently of the action of said spring return 30 means.

34. In an apparatus for preparing control strips for linecasting machines, indicating means, spring return means therefor, a counting clutch comprising a normally clamped gear, a rack 35 cooperable with said gear for controlling said indicating means, disabling means having a predetermined period of operativeness for unclamping said gear, and means controlled by said disabling means to effect during said period the 40 restoration of said rack to its initial position independently of the action of said spring return means.

35. In an apparatus for preparing control strips for linecasting machines, indicating means, spring return means therefor, a counting clutch comprising a normally clamped gear, a rack 45 cooperable with said gear for controlling said indicating means, means having a predetermined period of operativeness for unclamping said gear, and resilient means controlled by said last recited means to effect during said period the restoration of said rack to its initial position independently of the action of said spring return 50 means.

36. In an apparatus for preparing control strips for linecasting machines, indicating means, spring return means therefor, a counting clutch comprising a normally clamped gear, a rack 60 cooperable with said gear for controlling said indicating means, means having a predetermined period of operativeness for unclamping said gear, and a booster device controlled by said last recited means to effect during said period the restoration of said rack to its initial position independently of the action of said spring return 65 means.

37. In combination in an apparatus for preparing control strips for typographical machines, a signal determining means operable variably to 70 impress signals on said control strip, a counting device comprising a normally clutched gear, selector mechanisms for said devices, a unit carrying a plurality of coded elements, pivoted means for supporting said unit provided with a pair of 75

studs, means comprising a pair of bell crank levers having a common link therebetween, means articulated to said common link and controlled selectively through one of said selector mechanisms to shift said pivoted means to change the position of said unit with respect to the other of said selector mechanisms, means to control said counting device irrespective of said change of position of said unit, means for indicating the action of said other selector mechanism on said counting device corresponding to the variable operation of said signal determining means, a rack cooperable with said gear for controlling said indicating means in accordance with the operation of said counting device, means having a predetermined period of operativeness for de-clutching said gear, and means controlled by said last recited means to effect during said period the restoration of said rack to its initial position independently of the operation of said indicating means.

38. In a keyboard apparatus, a series of keys, a mechanism comprising means to totalize various additive amounts and to indicate continuously such totalizations, a unit carrying a plurality of coded elements, a parallel motion means for supporting said unit, said unit being adapted to be interchangeably insertable in said supporting means in operative relation to said keys for interchange according to the font of type to be used, and means controlled by certain of said keys to shift said parallel motion means to determine the shift or unshift position of said unit.

39. In a keyboard apparatus, a series of keys, a counting mechanism comprising means to totalize various additive amounts and to indicate continuously such totalizations, a unit carrying a plurality of coded elements, a parallel motion means for supporting said unit, said unit being adapted to be interchangeably insertable in said carrier, means in operative relation to said keys for interchange according to the font of type to be used, a pair of studs mounted on said parallel motion means comprising a pair of bell crank levers having a common link therebetween associated with said studs, and means articulated to said common link individual to certain of said keys and controlled thereby to shift said parallel motion means to determine the shift or unshift position of said unit. 5

40. In a keyboard apparatus, a series of keys, a counting mechanism comprising means to totalize various additive amounts and to indicate continuously such totalizations, a unit carrying a plurality of coded elements, parallel motion means for supporting said unit provided with a pair of studs, means comprising a pair of bell crank levers having a common link therebetween associated with said stud, and means comprising a pair of parallel code bars responsive selectively to certain of said keys to shift, through said link, said parallel motion means to determine the position of said unit. 20 25
